UNITED STATES PATENT OFFICE.

EDWARD A. LANGENBACH, OF CANTON, OHIO.

DESIGN FOR A BORDER-PLATE.

SPECIFICATION forming part of Design No. 26,242, dated November 3, 1896.

Application filed September 23, 1896. Serial No. 606,784. Term of patent 7 years.

To all whom it may concern:

Be it known that I, EDWARD A. LANGENBACH, a citizen of the United States, and a resident of Canton, county of Stark, State of Ohio, have invented and produced a new and useful Design for Metallic Border-Plates, of which the following is a full, clear, and exact description, reference being had to the accompanying drawings, making part of this specification.

The invention relates to a new design for metallic borders; and it consists of a strip of metal of the form and ornamentation shown in the accompanying drawings, in which—

Figure 1 is a plan view of the design for a border, and Fig. 2 is a sectional view of the same.

The leading feature of the design is a strip of metal formed with the longitudinally-ex-

tending bulge 1; the parallel bulge 2, arranged below the bulge 1 and less abrupt than the bulge 1; the flat marginal upper and lower edges 3 and 4, respectively, having raised ribs 5, alternating with circular ribs 6; the cone-shaped ribs 7, inclosing fan-shaped figures 8 and separated by arrow-heads 9; the vertical ribs 10, separated by triangular heads 11, and short vertical lines 12.

What I claim is—

The design for metallic borders, as herein shown and described.

In testimony whereof I have hereunto set my hand this 30th day of July, A. D. 1896.

EDWARD A. LANGENBACH.
